(57) **CLAIM**

What is claimed is the ornamental design for a planter, as shown and described.

DESCRIPTION

FIG. 1 is a perspective view of a planter showing a new design;

FIG. 2 is a front view of the planter of FIG. 1;

FIG. 3 is a side view of the planter of FIG. 1;

FIG. 4 is a top view of the planter of FIG. 1; and,

FIG. 5 is a bottom view of the planter of FIG. 1.

The portions of the planter shown in broken lines are included for the purpose of showing features that form no part of the claimed design.
